UNITED STATES PATENT OFFICE

2,529,491

SMOKE CONTROL

John Gadzuk, Drexel Hill, Pa.

Application March 4, 1947, Serial No. 732,360

2 Claims. (Cl. 98—58)

(Granted under the act of March 3, 1883, as amended April 30, 1928; 370 O. G. 757)

1

This invention relates to directional smoke-control apparatus for use on aircraft carriers, other vessels and land installations.

On aircraft carriers, especially during combat, landing of planes is difficult and accidents frequently occur. Because the plane and the carrier must be heading into the wind for landing, smoke and fumes from the smoke pipe trail the carrier, obscuring the pilot's vision and impairing breathing, thereby making landing more hazardous. On carriers having dual port and starboard smoke pipes, the flight deck can be kept clear of smoke and fumes by means of manually-operated by-pass dampers that allow smoke to be discharged from one side of the ship only. However, the controls for these dampers are below the flight deck and during changing wind direction there is sometimes confusion as to which position the damper should occupy.

It is an object of this invention to provide an apparatus for automatically controlling dual smoke pipes on an aircraft carrier to discharge smoke and fumes to the leeward side of the carrier.

On passenger-carrying vessels it is desirable to eliminate the nuisance of smoke and fumes especially if the decks are used by passengers. The decks can be kept clear of smoke and fumes by providing the vessel with a multiple smoke pipe having outlets terminating on the port and starboard sides and/or aft and providing by-pass dampers that allow smoke and fumes to be discharged from a selected outlet only. Smoke and fumes can be automatically discharged to the leeward side of the vessel by means of the invention described herein.

It is another object of this invention to provide multiple smoke pipes on vessels other than aircraft carriers and to provide these smoke pipes with an apparatus for controlling automatically a selected outlet to discharge smoke and fumes to the leeward side of the vessel.

On land installations whereby combustion gases and/or manufacturing fumes and gases are discharged to the atmosphere, it is sometimes necessary to isolate a certain section of the plant or neighborhood from the contaminating and nuisance effect of these gases. The discharge of these gases can be controlled and isolated by providing multiple discharge ducts and/or smoke pipes having outlets terminating at various strategic points and providing by-pass dampers that automatically allow smoke or commercial fumes and gases to be discharged to the leeward side only. The automatic control is by means of the invention described herein.

It is another object of this invention to provide multiple smoke pipes or discharge ducts for the control of smoke, gases and fumes discharged to the atmosphere and to provide an apparatus

2

for automatically controlling discharge of the smoke and fumes to the leeward side.

Further objects and advantages of this invention, as well as its construction, arrangement, and operation, will be apparent from the following description and claims in connection with the accompanying drawings, in which:

Fig. 1 is a plan view of one embodiment of this invention as adapted to a smoke pipe having two outlets;

Fig. 2 is a front view of the apparatus shown in Fig. 1; and,

Fig. 3 is a wiring diagram of the embodiment shown in Fig. 1.

There is shown in Fig. 1 and Fig. 2 a smoke pipe 11 having outlets on opposite sides of a ship, two wind-direction indicators 12 and 14, such as weather vanes, mounted above the deck and exposed to the wind, a by-pass damper 16, an electric motor 18 geared to operate damper 16, and relays 20 and 22 and limit switches 24 and 26 to control motor 18.

Wind-direction indicators 12 and 14 each consist of a vane 27 adapted to turn to point into the wind, a vertical shaft 28 on which the vane is mounted, and attached to vertical shaft 28 a spring contact 30 that can make contact with contact element 32. Contact elements 32 are so placed in wind-direction indicators 12 and 14 that when the wind is blowing in the direction shown, indicator 14 completes an electric circuit to cause motor 18 to turn damper 16 to position shown and when the wind is blowing from the other side of the ship, indicator 12 completes an electric circuit to cause motor 18 to make damper 16 to the opposite position.

The control circuit for motor 18 is shown in Fig. 3. Spring contact 30 is shown making contact with contact element 32 in wind-direction indicator 14 but not in wind-direction indicator 12. Therefore, relay 22 is energized causing the contacts to close, thereby connecting motor 18 to the power supply to drive damper 16 to the position shown in Fig. 2. When damper 16 reaches this position, it operates limit switch 26 to break the electric circuit and disconnect motor 18. When the wind shifts sufficiently to cause spring contact 30 and contact elements 32 of wind-direction indicator 12 to touch, relay 20 is energized and its contacts close. The contacts of relay 20 connect one of the motor windings 18a in the same manner as before, but winding 18b is reversed thereby causing motor 18 to rotate in the opposite direction until the circuit is broken by limit switch 24.

The wind-direction indicators 12 and 14 do not make contact when the wind is directly ahead or directly behind the ship so that indicators 12 and 14 cannot both make contact at the same

time and cause a short circuit across the power supply.

For use on carriers having smoke pipes on only one side of the ship, a small smoke pipe running from the main smoke pipe to the opposite side of the ship can be installed. This additional smoke-pipe is to be used in conjunction with this invention and only during landing of plane.

It is to be understood that various modifications and changes may be made in this invention without departing from the spirit or scope thereof as set forth in the appended claims.

The invention described herein may be manufactured and used by or for the Government of the United States of America for governmental purposes without the payment of any royalties thereon or therefor.

What is claimed is:

1. Apparatus for controlling discharge of gas from a smoke pipe, said apparatus comprising a first outlet in the smoke pipe and second outlet in the smoke pipe opposed to the first outlet; a damper movable into first position to open the first outlet and close the second outlet and movable into second position to open the second outlet and close the first outlet; an electric motor for rotating in one direction to move said damper into first position and for rotating in the opposite direction to move said damper into second position; an electric circuit including said motor, including limit switches for preventing movement of said damper beyond first position and second position, and including selector means for controlling the direction of rotation of said motor to move selectively said damper into first position or second position, and means responsive to the direction of the wind for operating said selector means.

2. Apparatus for controlling discharge of fluid from a conduit, said apparatus comprising a first outlet in the conduit and a second outlet in the conduit opposed to the first outlet; a valve movable into first position to open the first outlet and close the second outlet and movable into second position to open the second outlet and close the first outlet; an electric motor for rotating in one direction to move said valve into first position and for rotating in the opposite direction to move said valve into second position; an electric circuit including said motor, and including selector means for controlling the direction of rotation of said motor to move selectively said valve into first position or second position; limit means for preventing movement of said valve beyond first position and second position; and means responsive to the direction of fluid flow externally of said conduit for operating said selector means.
